ASH RECEIVER

Rudolph F. De Boer, Grand Rapids, Mich.

Application September 16, 1935, Serial No. 40,677

6 Claims. (Cl. 206—19.5)

This invention relates generally to a container and more particularly to a distinctive style of container and its novel mounting upon the instrument panel or the like of an automobile.

Briefly described, my invention relates to a tiltably mounted container which may be expediently removed and replaced from its support.

One main feature of my invention resides in its construction whereby a centrally located exposed knob serves two purposes, first, the knob serves to tilt the container and second, it serves to release the container for complete withdrawal movement.

Another feature of my invention resides in its construction whereby accidental release is absolutely prevented inasmuch as a definite manipulative movement must be made in order to unlock the container, but yet the container can be merely pushed into a locked position as will be explained later.

Another feature resides in the beauty or design of my container, this resulting from the vertical groove or indentation of the ornamental front panel of the container whereby a chromium strip or the like may be placed therein.

Another feature is the lower spring hinge construction, this spring plate being curved as shown so as to push upwardly against the central part of the bottom member of the container whereby the same is evenly seated against the cover or roof thereof.

Yet another feature resides in the positioning of the operating shaft for the unlocking means whereby it serves as means against which the ashes of the cigars or cigarettes can be flicked in either direction. Also, it is to be noted that the shaft is below the top of the container whereby the ashes, detached, are shielded from lateral air currents. Such currents, if not guarded against might tend to scatter the ashes interiorly of the car.

Another advantage is my construction whereby in the spring tends to hold the device in locked position of the detent or frictional element upon the resilient roof member or cover, struck from the instrument panel, whereby a resilient mounting is had. Therefore, the container is easily opened or closed. In this regard it is to be noted that the lower spring member permits vertical movement of the container. The container is held against the instruck portion of the instrument panel whereby smoke leakage is prevented and of more importance, the upper

front portion of the container is held against the front of the instrument panel to prevent smoke leakage at this point.

Other advantages will become apparent as the description progresses.

In the drawing:

Fig. 1 is a view in cross section taken along the line 1—1 of Fig. 2.

Fig. 2 is a rear view of Fig. 1.

Fig. 3 is a side view of my improved ash container in a position ready for use. The upper right hand corner of the container proper is broken away to show the releasable stop means.

Fig. 4 is an enlarged fragmentary view showing the stop means turned to an inoperative position. This view is taken at the rear side of Fig. 3 but with the stop means turned to an inoperative position.

Fig. 5 is an enlarged view taken along the lines 5—5 of Fig. 1.

Fig. 6 is a fragmentary view of the movable stop means.

Fig. 7 is a rear view of a modification of my invention.

Fig. 8 is a side view of Fig. 7 with the ash container tilted forwardly to its operative or usable position.

Fig. 9 is a rear view of the container proper.

Fig. 10 is a sectional view through the rear upper corner of the container.

Fig. 11 is a horizontal fragmentary view through the front wall of the container.

Like numerals refer to like parts throughout the several views.

Referring primarily to Figs. 1, 2, and 3, numeral 10 indicates the bottom of the ash container. The bottom is continued upwardly at one side to form the back wall 11 and at the other side to form the front wall 12. Side walls 13, having right angled flanges 14 around all but their top edges overlap and are fastened to the outer sides of the bottom and the front and back walls.

A front ornamental plate 15, see Figs. 1 and 11, is located against the overlapped portions or flanges 14. The central portion of this plate 15 is paneled inwardly so as to contact against the front wall 12 and it may be welded thereto at 16 if desired. A strip 17, of artistic creation, is placed in the depression in the plate 15 and has extensions 18 at each end. These extensions are bent around the ends of the several members in order to hold them together. See Figs. 1 and 9.

The front wall 12 and its adjacent members

have an opening therethrough which receives the eyelet 20. A shaft 21, having an operating knob 22, is rotatably mounted in the eyelet and an alined opening through the rear wall 11. This 5 opening is surrounded by the concentric depressed portion 23 which receives the coiled spring 24. A disc 25, cut away as shown at 26, is headed onto the end of the shaft 21 as indicated at 27. Thus rotation of the shaft causes 10 rotation of the disc. The coiled spring 24 has one end fastened at 28 to the disc 25 and the other end connected in any suitable manner to the rear wall 11. This causes the disc to assume the position as shown in Fig. 2 whereby outward 15 swinging movement of the ash container is limited.

This limiting occurs when the disc 25 hits against the stop 30 on the inbent portion 31 of the instrument panel 32. A detent or latch element 33, see Figs. 1 and 3, is provided upon the lower side of the inbent portion 31.

The rear wall of the container is cut away at 35 and a lug 36 is provided adjacent thereto. The slot 35 permits swinging withdrawal of the container as the stop 30 passes through the slot and the lug 36 limits the turning movement of the disc 25.

A spring plate 40 is welded at 41, see Fig. 2, onto the rear wall of the container between the flanges 44. This plate is bent to medially contact the bottom 10 of the container and then extends downwardly and terminates in a short flange 42 and adjacent lugs 43.

The lower edge of the instrument panel opening has an upwardly extending lip 44, this lip being received between the elements 42 and 43 and thereby forming a hinge.

Referring now to Figs. 7, 8, 9, and 10, in which a modification is shown, it is to be seen that the 40 basic construction is the same.

The rear wall 11, in this modified form, has a rearwardly turned flange 50, see Figs. 8 and 10, whereby the container may swing forwardly to its wide open position without becoming released by being forced upwardly due to the spring plate 40.

As shown in Fig. 10, the shaft 21 has a cross locking member 51 headed thereto at 52. A spring 53, similar to the spring 24, extends between the cross member 51 and the rear wall 11 and turns the cross arm 51 to the position shown in Fig. 7. This is its operative position inasmuch as the ends of the arm will hit against the inner sides of the opening through the instrument 55 panel. See Fig. 8.

A guiding and shielding member 55, of suitable shape, encloses the cross arm as shown, and limits its movement. The member 55 is welded to the back at 56.

60. Slots 57, see Fig. 7, are provided alongside of the opening through the instrument panel in order to permit the reinsertion of the ash container without turning the knob and its shaft. The container is inserted by moving it directly 65 inwardly to position thus causing the ends of the cross arm to pass through the said slots.

The operation

70. In order to use the container, the knob 22 is grasped and pulled outwardly thereby pulling the upper edge of the rear wall 11 over the detent 33 and then causing the container to move about its hinge to assume the position shown in Fig. 3. As 75 the spring 24 is effective, the shaft and its disc

25 are located as shown in Fig. 2 whereupon the disc 25 will contact the stop 30.

The device is, of course, returned to its concealed position by pushing inwardly upon the knob 22.

If it is desired to bodily remove the container in order to empty the same, then the knob 22 and its shaft 21 are rotated so as to place the disc in the position shown in Fig. 4. It is to be noted that the lug 36 limits the rotation of the 10 disc in both directions. The container is now free to be tilted outwardly until the rear wall 11 thereof clears the opening of the instrument panel and removal is had.

Reinsertion of the container may be accomplished by reversing the process just set forth, or if desired, the reinsertion may be accomplished by straight movement of the container into and through the opening in the instrument panel. This is possible because the inner vertical dimension of the container is less than the same dimension at its front edge. When this is done, the lugs 43 slide over the lip 44 and thus the pivotal connection is completed between the container and its support.

The modification shown and disclosed operates as described except that the cross arm 51 contacts the instrument panel at its sides rather than at its top. The cross arm 51 can be rotated to its inoperative position shown in Fig. 9 to accomplish the removal of the container.

Having thus revealed this invention, I claim as new and desire to secure the following combinations and elements, or equivalents thereof, by Letters Patent of the United States:

1. In combination, a mounting plate having an opening therethrough, a container, a detachable hinge member cooperatively associated with the mounting plate adjacent one edge of the opening, spring means for mounting the hinge member on the container, a knob attached to the container whereby the same may be moved about its hinge member, means for limiting the outwardly swinging movement of the container and means acting in conjunction with the knob for releasing the 45 said limiting means.

2. In combination, a mounting plate having an opening therethrough, a container hinged to one edge of the opening and swingable thereabout, stop means for limiting the movement of the container in one direction, a knob attached to the container to serve as means for swinging the same and means cooperatively associated with the knob and stop means whereby movement of the knob relatively to the container releases the stop 55 means.

3. A combination of elements as set forth in claim 2 in which the cooperatively associated means includes a rotatable shaft, the knob being mounted upon one end thereof and the stop 60 means on the other.

4. In combination, a mounting panel having an opening and a stop near the top of the opening, an ash container having a back, front, sides and bottom pivoted to swing behind and through the opening, a shaft revolubly mounted in the front and back walls, a knob on the front end of the shaft, locking means rigidly attached to the shaft, said shaft and locking means being rotatable so as to contact or miss the said stop on the panel 70 during swinging movement of the container, a coiled spring tensioned between the shaft and the container and rotating the locking means to a position whereby it contacts the stop on the panel when the ash container is swung forwardly.

5. A combination of elements as set forth in claim 4, in which the coiled spring is housed within a stamped depression in the back of the ash container.
5. A device of the class described comprising, a frame, a container mounted for inward and outward movement in said frame, stop means at the rear of the container, additional stop means near

the front of the said frame, said pair of stop means normally engaging one another to limit the outward movement of said container, a knob on said container and means actuated for manipulation by said knob for disengaging said outward stop means to permit withdrawal of said container from said frame.

RUDOLPH F. DE BOER.
